UNITED STATES PATENT OFFICE

2,461,318

ELECTRIC CLOTHES DRIER

Arthur J. Folli, Chicago, Ill.

Application April 8, 1946, Serial No. 660,437

6 Claims. (Cl. 34—151)

1

The invention relates to improvements in dryers for washed clothing or the like, but more particularly to electrically operated devices of this kind which are used in quickly drying small hand-washed articles such as stockings, lingerie, baby clothes and the like, and has for its objects the provision of such a device which will be simple in construction, convenient and safe to operate, and highly efficient in use.

Other objects will appear hereinafter.

The invention consists in the combinations and arrangements of parts hereinafter described and claimed.

The invention will be best understood by reference to the accompanying drawings forming a part of this specification and in which

Figure 1 is a top plan view of such a device embodying the invention and as arranged for use:

Figure 2 is a front view having a part of the housing broken away to illustrate the arrangement of parts within, and

Figure 3 is an enlarged section taken on line 3—3 of Figure 2.

The embodiment of the invention illustrated in the drawings comprises a suitable housing 10 of hollow construction, having walls of substantially even thickness, and provided at its back with a rearwardly extending T headed bracket 11 adapted to be attached by ordinary means to a wall or the like in a convenient place for use.

Inwardly of the bracket 11 is an inwardly projecting arm 12 adapted to support an electric motor 13 in vertical position carrying on the upper end of its rotor shaft 14 a three-bladed blower fan 15 arranged and adapted to draw air through a plurality of slotted openings 16 located in the top of the housing 10 and to discharge such air horizontally within said housing 10. The blower fan 15 is arranged in a suitable recess 17 which communicates with recesses 18 opening downwardly on each side of said recess 17. Arranged within the recesses 18 are centrally suspended heating elements 19 comprising a cylindrical body 20 having a conical shaped base 21 unitarily constructed of a dielectric heat resisting material and provided on its surface with a helically wound resistance wire 22. The heating elements 19 are attached to the housing 10 by suitable screws 23 mounted in threaded openings in the upper end of cylindrical bodies 20.

The housing 10 is provided with a downwardly and outwardly extending skirt 24 beneath which articles to be dried are placed. To facilitate the placing of a number of articles at the same time

5 a pair of parallel spaced rods 25 connected at their opposite ends to downwardly and outwardly projecting inverted V shaped brackets 26 attached as shown to the ends 27 of the skirt 24.

10 The rods 25 are provided with a plurality of slideable clamps 28. The clamps 28 are substantially the same as the conventional clothes pin of that type with the exception of the clamp arm 29 which is provided at its outer end with a hole 30 for mounting on the rods 25, as best shown in Figures 2 and 3.

15 The device is operated by electricity from the usual house current carried through the electric cord 31 which in turn is carried to the motor 13 and the heating elements 19 by the usual system of wiring (not shown) for connecting such combinations, as will be readily understood.

20 When the device is in use, air is drawn in through the slotted openings 16 by the blower 15 it is divided into two streams and forced through the recesses 18 contacting the heating elements 19 and discharged through the converging recesses 18 thereby creating a zone of swirling heated air immediately below the housing 10 and against the articles suspended from the rods 25, as will be readily understood.

25 While I have illustrated and described a preferred form of construction for setting forth the arrangement of parts of my invention, I do not wish to be limited by the precise details thereof but desire to avail myself of such variations and modifications as may fall within the spirit and scope of the appended claims.

30 I claim:

1. An electric dryer of the class described comprising a housing having a chamber in its uppermost portion; a fan arranged horizontally within said chamber; a grille formed in said housing 40 above said fan for the admission of air; an electric motor mounted within said housing below said fan chamber and operably connected to said fan; side air passageways on opposite sides of said fan chamber and communicating therewith; 45 vertical air passages extending downwardly from said side air passageways; an inverted cup air space communicating with both of said vertical air passageways; air heating element arranged in each of said vertical passageways; and clothes supporting means arranged below said housing in spaced relation thereto in the path of air discharged from said housing.

50 2. The construction specified in claim 1 in which the fan and fan chamber are of a centrifugal type having an air intake at one side

2

and a tangential discharge at opposite sides of said fan chamber.

3. The construction specified in claim 1 in which the heating elements are suspended in vertical air passageways.

4. The construction specified in claim 1 in which the heating element supports are provided with enlarged outer ends arranged and adapted to create divergent air currents.

5. The construction specified in claim 1 in which the heating element supports are suspended within a vertical air passageway from said housing.

6. A dryer of the class described comprising a housing open at its bottom and provided at its top with an air intake opening; a centrifugal blower arranged horizontally adjacent said opening; divergent air passageways receiving air from said blower; tortuous passageways for conveying

air downwardly within said housing; heating elements arranged within said passageways; means for diverging the flow of air horizontally at the place of discharge; and clothes holding means arranged within circulating range of air discharged from said blower.

ARTHUR J. FOLLI.
